US0D1060225S

(12) **United States Design Patent** (10) Patent No.: **US D1,060,225 S**
(45) Date of Patent: ** Feb. 4, 2025

(54) **CHARGER PLUG**

(71) Applicant: **C-Smartlink Information Technology Co., Ltd.**, Shenzhen (CN)

(72) Inventors: **Jon Zhang**, Shenzhen (CN); **Ady Liu**, Shenzhen (CN); **Sam Liu**, Shenzhen (CN)

(**) Term: **15 Years**

(21) Appl. No.: **29/862,816**

(22) Filed: **Dec. 13, 2022**

(51) LOC (15) Cl. **13-02**

(52) U.S. Cl.

USPC **D13/107**

(58) **Field of Classification Search**

(57) **CLAIM**

The ornamental design for a charger plug, as shown and described.

DESCRIPTION

FIG. 1 is a front perspective view of a charger plug, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the charger plug, which form no part of the claimed design.
